US00D908725S

(12) **United States Design Patent** (10) **Patent No.:** **US D908,725 S**
Araki (45) **Date of Patent:** ** *Jan. 26, 2021

(54) **DISPLAY SCREEN WITH TRANSITIONAL GRAPHICAL USER INTERFACE**

(71) **Applicant:** **THE YOKOHAMA RUBBER CO., LTD.**, Tokyo (JP)

(72) **Inventor:** **Yasuhiro Araki**, Hiratsuka (JP)

(73) **Assignee:** **THE YOKOHAMA RUBBER CO., LTD.**, Tokyo (JP)

(*) **Notice:** This patent is subject to a terminal disclaimer.

(**) **Term:** **15 Years**

(21) **Appl. No.:** **29/682,633**

(22) **Filed:** **Mar. 6, 2019**

(30) **Foreign Application Priority Data**

Sep. 6, 2018 (JP) 2018-019468

(51) **LOC (13) Cl.** **14-04**

(52) **U.S. Cl.**

USPC **D14/486**

(58) **Field of Classification Search**
